UNITED STATES PATENT OFFICE.

FARNUM F. DORSEY, OF ROCHESTER, NEW YORK, ASSIGNOR TO SENECA CAMERA
MANUFACTURING COMPANY, OF ROCHESTER, NEW YORK.

SPRING-ADJUSTING MECHANISM.

1,078,134.

Specification of Letters Patent.

Patented Nov. 11, 1913.

Application filed March 13, 1912. Serial No. 683,637.

To all whom it may concern:

Be it known that I, FARNUM F. DORSEY, a citizen of the United States, and resident of Rochester, in the county of Monroe and 5 State of New York, have invented certain new and useful Improvements in Spring-Adjusting Mechanism, of which the following is a specification.

This invention relates to mechanism for 10 adjusting the tension of a spring, and is particularly applicable to shutters of the roller-blind type, wherein spring-actuated rollers are employed to actuate flexible curtains.

15 The object of the invention is to produce a tension-adjusting mechanism in which a single, rotary, manually-operable member may be employed both for the purpose of increasing the tension, and for the purpose 20 of decreasing the tension, this member being manually rotated in one direction or the other according to the nature of the adjustment required, but being securely held, normally, against movement under the influence 25 of the spring.

To the foregoing end I employ a construction in which the detent, or means for retaining the manually-operable member and the spring in adjusted position, operates 30 yieldingly, so that upon the application of a force slightly greater than the force of the spring the effect of the detent may be overcome, and the manually-operable member rotated in either direction. In the preferred 35 embodiment of the invention I also employ a detent-mechanism of such form and construction that the resistance to rotation of the manually-operable member is comparatively slight when the latter is rotated in 40 a direction to increase the tension of the spring, while against rotation in the opposite direction the detent-mechanism opposes a greater resistance, sufficient to effectually 45 overcome the tendency of the spring to rotate the member.

The invention will be more particularly set forth in the following description of the embodiment illustrated in the accompanying drawings, in which—

50 Figure 1 is a side-elevation of parts of a roller-blind shutter embodying the present invention; Fig. 2 is a front-elevation of the parts shown in Fig. 1, in section on the line 2—2 in the latter figure; and Figs. 3 and

4 are detail-views, on a larger scale, illustrating the operation of the cam and the detent-arm under different circumstances. 55

While my invention may be embodied in roller-blind shutters of various types, I have illustrated it, for convenience, as embodied 60 in a shutter such as that disclosed in the patent to Joseph Goddard, No. 1,009,501, granted November 21, 1911, and I have, therefore, shown in the drawings only so much of the shutter as is necessary for an understanding 65 of the application thereto of the present invention. As in the shutter of said patent, the illustrated shutter has the usual flexible curtain 6, which is normally wound upon an upper roller 7, from which it is drawn in 70 the production of an exposure, being rewound upon a spring-actuated roller 8 at the bottom of the mechanism. In passing from the roller 7 to the roller 8 the curtain is directed by guide-rollers 9 in the usual manner. 75

The spring-roller 8 is hollow, being constructed of a metal tube, and within it is inclosed a long helical spring 10, as is usual in such constructions, one end (not shown) of the spring being fixed to the roller, while 80 the other end is fixed, as shown in Fig. 2, to a shaft 11 which passes through the center of the roller. The roller is provided at the end with a bushing 12, fixed to the tube and free to rotate upon the spring-shaft 11. The 85 shaft thus constitutes a bearing for the roller. The shaft is normally stationary, but it passes loosely through a plate 22 at the side of the shutter, and may be rotated in either direction, to increase or decrease the tension of 90 the spring.

For the purpose of rotating the spring-shaft as just described, the shaft is provided, at its outer end, with a milled head 13, as in said patent, this head constituting a manually-removable member which may be turned by the thumb and finger. The head is screwed upon the end of the shaft, and is also fixed in place by a set-screw 14. 95

The novel features of the present invention reside in the detent-mechanism by which the head 13 and the spring-shaft are normally held against rotation. To this end a cam 15 of oval or substantially elliptical form is fixed upon the inner end of the head 13, and this cam is engaged by a detent-arm 16 pivoted, at one end, upon a stud 17 100 screwed into the plate 22. The other end

of the detent-arm is connected with a spring 18, of which the upper end is fixed to a pin 19 projecting from the plate 22. The upper surface of the detent-arm 16 is curved to conform to the surface of the cam, so that in the normal position of the parts the arm rests closely against one of the long sides of the cam, as shown in Fig. 1. The spring 10 tends to rotate the spring-shaft and the cam 10 in the direction of the arrow in Fig. 1. This tendency is opposed, however, by the pressure of the detent-arm against the cam, the force of the spring 18 being sufficient to maintain the parts in the position of Fig. 1. 15 When it is desired to increase the tension of the spring 10, however, this may be readily done by rotating the head, and the parts connected therewith, in the direction of the arrow in Fig. 3. During this operation the 20 detent-arm is swung downwardly, against the resistance of the spring 18, by the rotation of the cam, but as the high points of the cam first engage the arm, at this time, near its free end, as shown in Fig. 3 at the point 25 20, the spring 18 and the detent-arm do not offer great resistance to the movement of the cam, and the parts may, therefore, be easily rotated for the purpose in question, by the application of a force only slightly greater 30 than that required to overcome the resistance of the spring 10. After each half-rotation of the parts, however, they again resume the position of Fig. 1, in which they tend to come to rest, and thus the spring-tension 35 may be increased by a succession of half-rotations of the head 13. To decrease the spring-tension the head 13 is rotated in the opposite direction, as in Fig. 4. At this time the detent-arm is also swung downwardly 40 by the cam, but the high points of the cam first engage the arm much nearer to its fulcrum 17, as at the point 21 in Fig. 4. Accordingly, the resistance of the detent-mechanism to rotation of the spring-shaft is sub- 45 stantially greater in this direction than in the opposite direction, being sufficient to more than overcome the rotative tendency of the spring 10. As the latter spring, however, assists the operator in rotating the 50 parts in this direction, the head 13 may be easily turned to decrease the tension, although securely held when in the position of Fig. 1.

By the construction just described I produce a mechanism in which the manually-operable rotatable member 13 may be easily turned in either direction, according as it is required to increase or decrease the tension of the shutter-spring. While I preferably 55 employ a cam and a resilient arm for this purpose, it will be understood that various equivalent arrangements may be employed for this purpose, and that the invention is not limited to the embodiment thereof specifically described.

I claim:—

1. Spring-adjusting mechanism having, in combination with a spring, a manually-rotatable member connected with the spring to adjust the tension thereof, and detent-mechanism comprising a part rotative with the manually-rotatable member, and a non-rotatable part coöperating with the rotary part, one of said parts having a cam-surface and one of said parts being spring-pressed to maintain the parts in engagement with a force sufficient to normally prevent rotation of the manually-operable member, said cam-surface being formed to have a repressive action on the spring-pressed part in both 80 directions of rotation of the manually-operable member, so that said member may be turned forcibly in either direction to increase or diminish the tension of the spring. 70

2. Spring-adjusting mechanism having, in combination with a spring, a manually-rotatable member connected with the spring to adjust the tension thereof, and detent-mechanism comprising a cam rotative with the manually-operable member, and a non-rotative part having a surface engaging the cam-surface, one of said parts being spring-pressed with a force sufficient to hold the cam normally against rotation, and one of said parts having a plurality of uniformly spaced projections, on its operative surface, formed to have a repressive action, on the spring-pressed part, in either direction of rotation of the cam, whereby a regularly fluctuating resistance to rotation 95 of the manually-operable member in both directions is produced, while said member may be forcibly rotated in either direction to increase or diminish the tension of the spring. 85

3. Spring-adjusting mechanism having, in combination with a spring, a manually-rotatable member connected with the spring to adjust the tension thereof, and detent-mechanism normally retaining said member in adjusted position, said mechanism comprising a cam rotative with said member, and a resiliently-yielding part coöperating with the cam, the cam having a high point which engages said part with increased force 110 so as to cause the manually-rotatable member to come to rest normally after a predetermined degree of rotation. 105

4. Spring-adjusting mechanism having, in combination with a spring, a manually-rotatable member connected with the spring to adjust the tension thereof, and detent-mechanism for retaining said member against rotation, said mechanism comprising a cam rotative with said member, and a resilient swinging arm coöperating with the cam, the cam having a high point which engages the arm, to swing it, nearer to the center of movement of the arm in one direction of rotation of the cam than in the 115 120 125 130

other direction of rotation, whereby rotation of the cam is resisted more strongly in one direction than in the other.

5. Spring-adjusting mechanism having, in combination with a spring, a manually-rotatable member connected with the spring to adjust the tension thereof, and detent-mechanism normally retaining said member against rotation, said mechanism comprising a substantially elliptical cam rotative with said member, a detent-arm pivoted on an axis parallel with the axis of the cam and having one side in engagement with the cam, and a second spring connected with the arm and forcing it into such engagement.

6. Spring-adjusting mechanism having, in combination with a spring and with a fixed support, a manually-rotatable member

connected with the spring to adjust the tension thereof, and detent-mechanism normally retaining said member in adjusted position, said mechanism comprising two detent-members of which one is in the form of a cam rotative with the manually-rotatable member, and the other is in engagement with the fixed support, one of the detent-members being spring-pressed and yieldable, to the action of the cam-surface, in either direction of rotation of the cam, when subjected, by the manually-rotatable member, to a rotative force greater than that normally sustained by the detent-members. 20 25 30
